(57) CLAIM

The ornamental design for a portable clothes valet, as shown and described.

DESCRIPTION

FIG. 1 is a perspective view of a portable clothes valet showing my new design;

FIG. 2 is a front elevational view thereof;

FIG. 3 is a rear elevational view thereof;

FIG. 4 is a left end elevational view thereof;

FIG. 5 is a right end elevational view thereof;

FIG. 6 is a top plan view thereof;

FIG. 7 is a bottom plan view thereof;

FIG. 8 is a perspective view thereof showing a clothes hanger mounted thereon; and,

FIG. 9 is a perspective view showing my portable clothes valet mounted on the top edge of a chest drawer with the valet supporting a jacket.

The portions shown in broken lines in FIGS. 8 and 9 are for information only and form no part of the instant design.
